UNITED STATES PATENT OFFICE.

MARTIN PRIOR BOSS, OF SAN FRANCISCO, CALIFORNIA.

CONCENTRATOR.

No. 878,861.

Specification of Letters Patent.

Patented Feb. 11, 1908.

Application filed May 21, 1906. Serial No. 317,936.

To all whom it may concern:

Be it known that I, MARTIN P. BOSS, citizen of United States, residing at the city and county of San Francisco and State of California, have invented new and useful Improvements in Concentrators, of which the following is a specification.

My invention relates to an apparatus for concentrating ores and is particularly designed to eliminate a clean gangue from a pulp, saving a product containing all the concentratable values not necessarily freed from gangue, but having greatly reduced volume for re-treatment in a more complete manner. It consists in the combination of mechanism and in details of construction which will be more fully explained by reference to the accompanying drawings, in which—

Figure 1 is a side elevation of my apparatus. Fig. 2 is a plan view. Fig. 3 is an end view. Fig. 4 is a plan of table. Fig. 5 is a longitudinal section. Fig. 6 is a side elevation. Fig. 7 is a transverse section. Fig. 8 is an enlarged transverse section of one of the grooves or channels, showing the decreasing depth. Fig. 9 is a longitudinal section showing the mechanism for reciprocating the table. Fig. 10 is a plan view of the same, and Fig. 11 is a transverse section through the crank shaft. Fig. 12 is a diagrammatic view illustrating the movement which takes place. Fig. 13 is a side view, and 14 is a plan of the bed and carriage. Figs. 15, 16 and 17 are details of the differential rollers and connections.

As shown in the present illustration, the device consists of a bed, a traveling carriage, a top or table proper, and head mechanism for producing a longitudinal reciprocation.

The bed A is firmly fixed or anchored by means of a transverse trunnion 2 about which it is tilttable so that the level of the table may be adjusted longitudinally. The bed A may be tilted upon its trunnions by means of vertically movable adjusting screws 3, or by any equivalent or suitable means. The carriage 3^a is movable longitudinally upon the bed being supported by differential rollers 4 which are supported by and travel in boxes 5 containing a lubricant in which the peripheries of the rollers are submerged, and the slow movement of the carriage in one direction, and the quick start of return movement in the other direction, produces a slight crawl or slip movement of the rollers, so that in time the entire face of

the rollers, will have been submerged in the lubricant, and the surfaces of the rollers will be prevented from becoming flattened by constant reciprocation upon one point.

The table top is mounted longitudinally with the carriage 6, and is tilttable from side to side, so that in conjunction with the adjustment of the bed, and the transverse tilting, the table top may be adjusted to any desired level or inclination. This transverse adjustment may be effected by connecting one side of the carriage to one side of the top by an intervening adjusting screw, as shown at 7. The table top may be made either of strips of the width of each channel, or it may be made up of wider pieces, grooved with several channels and bolted or otherwise secured together, having longitudinal channels from end to end, as shown at 8 in Figs. 7 and 8. These channels are preferably made with rounded bottoms for the easy collection and travel of the precipitates. They have an even depth for approximately one-half of their length; from which point they gradually diminish in depth, terminating with a depth of 1/8 of an inch. This difference of depth is well shown in enlarged view Fig. 8 of one of said channels.

The channeled table top forms a plane which is higher at one side than the other, as shown in Fig. 7, and in operation the pulp is fed on at the forward end of the high side of the table from any suitable source of supply, as at 9 Fig. 3, and it flows transversely across the said table with the resulting action of precipitation of the containing concentrates into the channels over which it passes. The channels filled with pulp have at the forward end of the table sufficient depth to greatly facilitate precipitation of the concentrates which are made to travel in a close body along the rounded bottom of each channel by means of the peculiar reciprocating movement. In ores of a slimy nature however, some of the concentratable values may be carried over the entire series of channels unless pulp is fed very slowly. To obviate this I affix a projecting shelf 10 to the lower side of the forward end of table, with its surface inclined toward the table in such a way that precipitates which may settle upon it will be returned into the lowermost of the longitudinal grooves or channels, as is plainly shown in Fig. 7.

In order to insure the return of all the material, the terminal end of shelf has a riffle or

raised portion, as shown at 11, which stands in oblique position with relation to the main portion of the table, and this oblique shoulder or abutment causes the divergence of the 5 precipitates back into the lowermost channel. The motion for reciprocating the table with a quicker start on the return at one end of the stroke, than the movement at the other end is effected by a driven shaft 15, which 10 has at one end a crank with a connecting rod or link 16, of a length approximating the length of the stroke of the crank. The path of the other end of the connecting rod or link is defined by a long anchoring link 17, one 15 end of which is connected with the link 16, and the other end with a fixed point of support about which the link 17 oscillates. The thrust bar or rod 18 has one end connected with the pin which connects the rod 17 with 20 the end link 16. The movement of the crank around its center, acting through the link 16, causes the rod 17 to oscillate about its fixed point of support 17^a. This movement acts through the connecting rod 18, the opposite 25 end of which is connected with the table 8, and it will be obvious that this connection produces a peculiar movement of the table.

Referring to the diagram Fig. 12, the 30 crank, being in a vertical upward position the first movement of the crank, as indicated by the arrow, acting through the link 16, and the connecting rod 17 and 18, will move the table longitudinally. The termination of the first eighth of this movement is indicated by the letter *a*, and during this movement the amount of movement of the table longitudinally will be indicated by the space *a'* at the opposite end of the diagram. The one-eighth movement between the point 35 marked *b* and the point *c*, which is at the bottom of the travel of the crank will produce a lesser movement of the table as indicated by the lines *b'*. The movement from the point *c* to the point *d* being the first one-eighth of 40 the arc in the upward movement of the crank from the bottom, causes a movement of the opposite end of the thrust rod, the distance to which is indicated by the space *d'*, and the final one-eighth of the return movement of the crank at the top of the circle 45 from the point *e* to its vertical position, causes a movement of the thrust rod and the table, the amplitude of which is indicated by the space *e'*. In order to regulate these 50 movements, and to give the table any required amount of motion, I have shown the point of connection of the rod 18 with the table, as being slidab

le end as shown at 19, and this movement 55 may be conveniently made by means of a connecting screw and a hand wheel as at 20. Thus if the point 19 be moved downwardly until it coincides with the fixed connection 60 17^a there will be no movement of the table, and as the point 19 is moved upwardly, and

to a greater distance from the point 17^a, the movement of the table will be correspondingly increased.

The principle of operation is based on the difference of deflecting a very short connecting rod or link from the thrust line convex to the anchored end of the link at one end of the stroke, and concaved at the other end. 70

Having thus described my invention, what I claim and desire to secure by Letters Patent is—

1. In a concentrator, a longitudinally and transversely adjustable table, with means for producing an abrupt longitudinal movement of the table, means for supplying pulp at the receiving or forward end of the table, said table having longitudinal channels forming settling and skimming zones, the first portion of which channels have substantially level bottoms, and the bottoms of the remainder gradually rising to the terminals of the channels, and a shelf projecting from the lower side of the table, said shelf inclining toward the table and having an elevated rib or riffle. 80

2. A concentrator having a plane surface with settling and skimming zones formed of longitudinal grooves or channels, the first portion of which have substantially level bottoms, and the remainder having bottoms gradually inclining upward from the ends of the first portion to the terminals of the channels, means for reciprocating the table, means for adjusting the inclination of the table, means for supplying pulp at the upper forward angle of the table, and a shelf projecting from the opposite side of the table and inclining toward the table, said shelf having an elevated rib or riffle at its lower end. 90

3. A concentrator table inclined transversely and having a head-end arranged obliquely to the sides, said table having a true plane surface, and longitudinal and transverse adjusting means, said table having, also, longitudinal grooves forming settling and skimming zones, the first portion of which grooves, have level bottoms, and the remainder having the bottoms inclining upwardly to the termination of the grooves, means for producing an abrupt longitudinal movement of the table, means for supplying pulp at the upper and head angle of the table, a shelf projecting from the opposite side of the forward end, said shelf having an inclination opposite to that of the table, and elevated ribs or riffles at its terminal end. 100

4. In a concentrator, a longitudinally and transversely adjustable table, with means for producing an abrupt longitudinal movement of the table, said table having longitudinal grooves or channels formed in its surface, with successive level and upwardly inclined bottoms, a shelf projecting from the opposite side of the forward end, said shelf 110

120

125

130

having an inclination opposite to the transverse inclination of the table, and a riffle or obstruction whereby material is returned from the shelf to the lowermost of the 5 grooves or channels of the table.

5. In a concentrator, an adjustable table in combination with means for inclining and adjusting the table transversely, a support upon which the table is carried, and means 10 for producing a variable longitudinal reciprocation of the table, said means including a rod connected with the table, an anchored rod having its outer end connected with the outer end of the table rod, and a revoluble 15 crank with which the outer ends of said rods are connected.

6. In a longitudinally grooved concentrating table having a transverse inclination, and a true plane surface, said table having 20 grooves with successive level and upwardly inclined bottoms thereby forming settling and skimming zones respectively, means for delivering pulp upon the upper forward angle of the table, a shelf projecting along the 25 forward and lower side of the table said shelf having a diagonally disposed riffle at the lower end, and mechanism whereby a variable abrupt movement of the table is produced in the direction of its length.

30 7. In a concentrator, a longitudinal and transversely adjustable table, with means for producing an abrupt longitudinal movement of the table, said table having longitudinal grooves or channels formed in its surface, 35 means for supplying pulp at the upper and head angle of the table, and a shelf projecting from the opposite side, said shelf inclining toward the table and having an elevated ridge or riffle at its lower end.

40 8. In a concentrator, a longitudinal and transversely adjustable table, with means for producing an abrupt longitudinal movement of the table, said table having longitudinal grooves or channels formed in its 45 surface, means for supplying pulp at the upper and head angle of the table, and an inclined shelf projecting from the opposite side of the forward end, said shelf inclining toward the table and having a rib or riffle.

50 9. In a concentrator, a longitudinal and transversely adjustable table, with means for producing an abrupt longitudinal movement of the table, said table having longi-

tudinal grooves or channels formed in its surface, means for supplying pulp at the upper and head angle of the table to flow transversely across the grooves, and a shelf projecting from the opposite side, said shelf inclining toward the table and having an elevated ridge or riffle at its lower end. 55 60

10. In a concentrator, a longitudinal and transversely adjustable table, with means for producing an abrupt longitudinal movement of the table, said table having longitudinal grooves or channels formed in its 65 surface, means for supplying pulp at the upper and head angle of the table to flow transversely across the grooves, and an inclined shelf projecting from the opposite side of the forward end, said shelf inclining toward the 70 table and having a rib or riffle fixed diagonally across its lower end.

11. In a concentrator, a longitudinal and transversely adjustable table, with means for producing an abrupt longitudinal movement of the table, said table having longitudinal grooves or channels formed in its surface, 75 means for supplying pulp at the upper and head angle of the table to flow transversely across the grooves, a shelf projecting from the opposite side of the forward end, 80 said shelf having an inclination opposite to the transverse inclination of the table, and a raised rib or riffle extending diagonally toward the table. 85

12. In a concentrator, a longitudinal and transversely adjustable table, with means for producing an abrupt longitudinal movement of the table, said table having longitudinal grooves or channels formed in its 90 surface, means for supplying pulp at the upper and head angle of the table to flow transversely across the grooves, a shelf projecting from the opposite side of the forward end, 95 said shelf having an inclination opposite to the transverse inclination of the table, and a riffle or obstruction whereby material is returned from the shelf to the lowermost of the channels.

In testimony whereof I have hereunto set 100 my hand in presence of two subscribing witnesses.

MARTIN PRIOR BOSS.
